UNITED STATES PATENT OFFICE.

SAMUEL S. DEARBORN, OF BOSTON, MASSACHUSETTS.

ROTARY SPINNING-RING.

1,204,346.

Specification of Letters Patent.

Patented Nov. 7, 1916.

Application filed December 19, 1910. Serial No. 598,195.

To all whom it may concern:

Be known that I, SAMUEL S. DEARBORN, a citizen of the United States, and a resident of Boston, in the county of Suffolk and State of Massachusetts, have invented 5 an Improvement in Rotary Spinning-Rings, of which the following description, in connection with the accompanying drawings, is a specification, like letters on the drawings 10 representing like parts.

This invention relates to rotary spinning rings.

In order that the principle of the invention may be readily understood, I have disclosed a single embodiment thereof in the 15 accompanying drawing, wherein—

Figure 1 is a plan view of a portion of a ring rail provided with a pair of rings embodying my invention; Fig. 2 is a side elevation thereof; Fig. 3 is a side elevation of 20 a form of holder that may be employed in the practice of my invention; Fig. 4 is a side elevation of one form of shield or casing for the exterior of the ring; Fig. 5 is a transverse vertical section taken through 25 the ring and holder and the exterior and interior ring shields or casings; Fig. 6 is a side elevation of one form of interior shield or casing for the ring; Fig. 7 is a similar 30 view of a slightly modified form thereof; and Fig. 8 is a plan view of still another slightly modified form of such shield or 35 casing.

An objection to the effective operation of 40 rotary spinning rings has been their tendency to accumulate lint and other foreign matter. Attempts have been made to exclude lint from rotary rings, but so far as I am aware without success. It has been 45 proposed to provide an exterior casing for the ring of a general bell shape, such casing constituting a bearing surface for the ring or with which the ring intermittently contacts during its rotation. In such construction, however, lint has readily accumulated 50 between the outer surface of the ring and the casing. In other cases the ring itself has been provided with a flange or member overlying a portion of the ring bearing, but 55 lint has readily found access to the ring and to its bearing. In still other cases an up-standing sleeve or member has been provided interiorly of the ring, and in most instances constituting an interior support or bearing for the ring, in no case, however,

so far as I am aware has such interior member excluded lint from the ring.

In accordance with the preferred embodiment of my invention I provide a fixed or stationary ring holder having lips or 60 tongues extending within the ring and constituting supports or bearings about or with respect to which the ring rotates with the customary or desired slight axial and radial movements in an ordinary or any suitable 65 manner. An important feature of my invention is the provision of a protector to exclude lint, dirt and other foreign matter from those surfaces upon which the ring rotates. In the illustrated embodiment of 70 my invention I provide both an interior and an exterior protector, which together exclude lint, etc., not only from the surfaces upon or with respect to which the ring rotates, but also from the ring itself from the 75 base thereof sufficiently toward the traveler so as preferably just to escape contact with the traveler in its rotation. It is evident, however, that the vertical extent of the shield or shields employed by me may be 80 varied within the scope of my invention. The upper portion of the ring is kept clear and free of lint, etc., by the traveler both 85 interiorly and exteriorly. Inasmuch therefore as the ring and the surfaces upon which it turns are thoroughly protected, the ring runs freely and evenly.

While the shield or shields constituting the casing may be variously constructed, 90 preferably and as herein illustrated they do not contact with the ring in its rotation either exteriorly or interiorly. Thereby, I avoid the wear that would be occasioned if the shield or shields constituted a portion 95 of the bearing surface or surfaces, and thus provide an effective protector which uniformly and equally protects the ring and its supporting surfaces indefinitely. Were the shield or shields subject to wear by reason of contact with the ring, it or they 100 would become enlarged in use, and hence less and less effective as a protector by reason of the increasing space between the ring and the protector into which the lint might work.

Referring more particularly to the drawings, the ring rail is indicated at 1 in Figs. 1, 2 and 5, it being provided with the customary openings for the spindles. Upon the ring rail I position in any suitable man- 110

ner any suitable ring holder. Herein I have shown a holder 2 having a substantially flat annular base 3, wherein the ring may rest when stationary and a flange 4 having slots 5, by means of which it may be secured by screws 6 or in any other suitable manner to the ring rail. Preferably the holder is provided with a clearer, such as 7, which may be if desired struck up from the holder, 10 the latter being preferably constructed of sheet steel. In order to permit the threading up of the traveler, it is desirable to place the clearer 7 at the rear of the ring rail, and it is at this point (that is, at the 15 rear of the rings) where the lint is liable to accumulate as the air currents from the spindle driving drum tend to drive the lint against the ring. The holder is provided with any suitable ring guiding means, such as 20 lips or tongues 8 bent upwardly from the base of the holder and received within the ring as illustrated. Herein I have represented a ring holder substantially similar to that shown in the patent to E. A. Brigham, No. 956,930, May 3, 1910, but it is evident that any other suitable holder may be employed, inasmuch as my invention is not dependent upon the type or form of holder or ring.

160 The rotary ring is represented at 9 in the several views, and while it may be of any desired form, it is here shown as similar to that illustrated in the said patent to Brigham. It is provided with the usual traveler race 10 and at its lower end flares outwardly as indicated at 11, and inwardly as indicated at 12, and when in a position of rest bears upon the holder face 3. The lips or tongues 8, which are here shown as 165 three in number and equally spaced, extend within the ring and are represented as flaring outwardly. Their position with respect to the traveler ring is such as to permit the latter to rotate at the proper speed under tension of the yarn upon the traveler, and also to permit the usual slight axial and radial centering movement not herein necessary particularly to describe, inasmuch as the form of the ring as well as of the supports may obviously be widely varied within 170 the scope of my invention. Although I have shown the lips or tongues 8 as extending within the ring, it is evident that exterior ring guiding means may be substituted therefor.

175 I contemplate the provision of suitable means to exclude lint and other foreign matter from portions of the rotating spinning ring herein for convenience termed the traveler ring, and preferably from both faces thereof below the path of the traveler as well as from the base or support whereon the ring is rotatable. To effect this result, I have in the described embodiment of my invention employed an outer shield 13 pref-

erably of annular form and herein shown as conforming substantially in shape to the outer face of the traveler ring below the path of the traveler. The vertical extent of said shield in some cases may be varied but 70 it is desirable that it extend from the base or support upwardly to substantially the path of the traveler and to terminate just below the path of the traveler, so that the traveler does not contact therewith in its rotation. 75

In the preferred embodiment of my invention it is exceedingly important that the shield extend upwardly to substantially the path of the traveler so as to exclude lint, etc., from the entire outer face of the ring that is below the path of the said traveler. Moreover the traveler keeps free from lint, etc., that portion of the traveler ring just below the traveler race, so that the traveler 85 and the shield 13 combine to keep the outer surface of the traveler ring clear and free from foreign matter. Preferably, the shield 13 is of such interior diameter that the traveler ring does not contact therewith at 90 any time, that is, neither when the ring is stationary nor when it has risen upon or with respect to the lips 8 in rotation. While I am not limited to a shield, such as 13, non-contacting with the outer face of the traveler 95 ring, yet by locating the said shield so that the traveler ring cannot contact therewith, it is evident that said shield is not subjected to wear, and hence maintains an unvarying relation with respect to said ring, and therefore at all times excludes lint therefrom. 100

The shield 13 is preferably made as a continuous ring of sheet steel or other suitable metallic matter, and is represented as provided with a base flange 14 fitting upon the 105 flange 4 of the base or support, and also provided with slots 15 to receive the screws 6 by which the base or support is secured to the ring rail. Preferably, also said base 14 is slotted as indicated at 16 for the passage 110 of the traveler clearer 7, as indicated in Fig. 1, or if desired the traveler clearer may be struck up from or otherwise formed upon the shield 13 itself. In the event that the traveler ring is provided with exterior supports or guides instead of interior supports or guides, as represented in this embodiment of my invention, it is evident that the character of the shield 13 would be modified to accord therewith. 115

In order to exclude lint and the like from the inner face of the traveler ring substantially below the path of the traveler as well as from the interior bearing or guides for the ring, I have in this embodiment of my 125 invention provided an interior ring 17 represented as split at 18, so that it may be sprung within the traveler ring and its supports and held fast with respect thereto against the base or support. While said 130

split ring 17 may be of any suitable material, I preferably form it of sheet steel of suitable thickness. Preferably, however, it is made so thin that it does not extend radially within the inner edge of the traveler race 10 as is evident from an inspection of Fig. 5, wherein that portion of said ring 17 that is of least diameter is represented as vertically in line with the inner edge of the traveler race 10. It is evident that said ring 17 may be of any suitable extent and form, but herein I have represented the same as having an outwardly extending base flange 19 and the portion of the ring there above as outwardly flaring as indicated at 20. Preferably the said ring 17 extends upward to substantially the top of the lips or guides 8 and at the upper edge thereof may be provided with a slight outwardly extending flange 21 resting upon the upper edge of said lips, but preferably not contacting with the inner face of the traveler ring. It will be noted that said ring 17 extends upward to a point just below the path of the traveler, so that it effectively shields the entire inner face of the ring below said traveler path. It will be evident therefore that the traveler ring in its rotation contacts only with the base or support, and preferably not with the shielding means either exteriorly or interiorly of the ring. Moreover, since the only rotary portions of the device are the traveler ring and its traveler, my invention presents no parts tending to attract or gather lint and other foreign matter.

It is evident that the ring 17 may be otherwise formed than as shown. For example, the split portion thereof may be formed as a tongue and groove, as represented at 22 in Fig. 7, or said ring may be split upon an incline as represented at 23 in Fig. 8, and preferably with the split edge slanting inwardly in the general direction of the rotation of the ring and its traveler, so that there is no tendency of the traveler to catch upon the split portion of the said ring 17.

It is evident from the foregoing description that the ring embodying my invention is of exceedingly simple construction, all complexity of parts being avoided, and that the ring both exteriorly and interiorly thereof as well as the ring guiding means, are effectively shielded from lint, etc. Furthermore, since neither the interior ring 17 nor the exterior ring 13 constitutes any portion of the ring guiding or supporting means, it is evident that there is no wear upon either of said shielding rings 13 or 14, and that they maintain an unvarying relation with respect to the traveler ring. Moreover, by so constructing and positioning the shielding ring 13 that it is at all times free from contact with the traveler

ring, there is no undue strain imposed upon the yarn as would be the case were the traveler ring to engage exteriorly with a surface of larger diameter.

Although I have herein represented the 70 shielding means as applied to a rotary ring of substantially the form shown in the Brigham Patent, No. 956,930, it is, of course, evident that my invention is in no wise restricted in its use to such form of ring, but 75 that the herein described shielding means may be applied to any suitable or desired form of rotary ring.

Having thus described one illustrative embodiment of my invention, I desire it to 80 be understood that although specific terms are employed, they are used in a descriptive and generic sense and not for purposes of limitation, the scope of the invention being set forth in the following claims. 85

I claim:

1. A rotary spinning ring comprising in combination a traveler ring rotatable by yarn tension, a traveler, a base or support whereon said ring is rotatable and having ring 90 guiding means extending within the traveler ring, and shielding means distinct from said guiding means to exclude lint, etc., from the latter, said shielding means being exposed to the clearing action of said traveler. 95

2. A rotary spinning ring comprising in combination, a traveler ring rotatable by yarn tension, a traveler, a base or support whereon it is rotatable and having ring guiding means extending within the traveler 100 ring, and stationary shielding means within said guiding means to exclude lint, etc., from said guiding means and exposed to the clearing action of said traveler.

3. A rotary spinning ring comprising in 105 combination, a traveler ring rotatable by yarn tension, a traveler therefor, a base or support whereon it is rotatable and having ring guiding means extending within the traveler ring, and stationary shielding means 110 distinct from and within the traveler ring and non-contacting with the latter, to exclude lint, etc., from said guiding means and from the inner face of the ring below the path of the traveler, said shielding means being exposed to the clearing action of the traveler. 115

4. A rotary spinning ring comprising in combination a traveler ring, a base or support whereon it is rotatable, and having ring guiding means extending within the traveler ring, and stationary shielding means distinct from said ring guiding means and positioned both interiorly of and exteriorly 120 to said traveler ring to exclude lint, etc., from the surfaces of the ring below the traveler and from said ring guiding means. 125

5. A rotatable spinning ring comprising in combination a traveler ring rotatable by 130 yarn tension, a base or support whereon said

ring is rotatable and having ring guiding means extending within the traveler ring and stationary shielding means distinct from and within the guiding means and non-contacting with the bearing surface of the latter to exclude lint, etc., from said guiding means and from the inner face of the ring below the path of the traveler.

6. A rotary spinning ring comprising in combination a traveler ring, a base or support whereon it is rotatable, and having ring guiding means extending within the traveler ring, a stationary shielding ring surrounding the traveler ring and extending from said base substantially to the path of the traveler, and a split, stationary shielding ring positioned interiorly with respect to said traveler ring and its ring guiding means and extending substantially to the upper edge of the latter, said shielding rings excluding lint, etc., from the outer and inner faces of said traveler ring below the path of the traveler and from said ring guiding means.

7. A rotary ring comprising in combination a traveler ring, a base or support therefor having an upstanding clearer, and a shielding ring surrounding the traveler ring, resting upon said base or support, and having an opening for the reception of said clearer.

8. A rotary ring comprising in combination, a traveler ring, a base or support therefor having upstanding ring-guiding lips extending interiorly of the ring and a stationary, ring-like shield positioned interiorly of the traveler ring and overlying said lips and spaced from said traveler ring in its positions of motion and rest, the portion of said

shield that is of least diameter being substantially vertically in line with the inner edge of the traveler race.

9. A rotary spinning ring comprising in combination, a traveler ring, a base or support whereon it is rotatable, ring guiding means extending within the traveler ring, and means exterior and also interior with respect to the traveler ring and extending substantially to the path of the traveler to exclude lint, etc., from all portions of the faces of the said traveler ring that are below the path of the traveler, the inner shielding means extending within said ring guiding means, the inner face of said shielding means being substantially equidistant with the inner edge of the traveler race of the traveler ring from the center of rotation of said ring.

10. A rotary spinning ring comprising in combination a traveler ring, a traveler therefor, a base or support for said traveler ring and having ring guiding means extending within the ring whereon said guiding means is rotatable, and a stationary shield distinct from said ring guiding means positioned interiorly of said traveler ring and extending up to the path of the traveler to exclude lint and other foreign matter from the entire portion of the inner face of said traveler ring that is below the path of the traveler.

In testimony whereof, I have signed my name to this specification, in the presence of two subscribing witnesses.

SAMUEL S. DEARBORN.
